UNITED STATES PATENT OFFICE

WILLIAM H. MUSSEY, OF CHICAGO, ILLINOIS, ASSIGNOR, BY MESNE ASSIGNMENTS, TO
PULLMAN CAR & MANUFACTURING CORPORATION, A CORPORATION OF DELAWARE

RAILWAY CAR TRUCK

Application filed April 26, 1929. Serial No. 358,226.

This invention relates to railway car trucks, and more particularly to railway car trucks carrying operating motors thereon.

One of the objects of the invention is the provision of a new and improved truck frame that is built up of individual elements and so constructed and arranged as to provide a structure having minimum weight and maximum strength.

10 Another object of the invention is the provision of a railway truck that is provided with new and improved means for supporting a motor for operating the car.

15 A further object of the invention is the provision of a new and improved truck frame constructed in such a manner as to give a minimum of weight with a maximum of rigidity.

20 A still further object of the invention is the provision of a new and improved truck frame that is cheap to manufacture, easily assembled, efficient in use, and that is light and rigid in construction.

25 Other and further objects and advantages of the invention will appear from the following description taken in connection with the accompanying drawings, in which

Fig. 1 is a side elevation of the truck;

20 Fig. 2 is a side elevation of a truck frame shown in disassembled position;

Fig. 3 is a plan view of one side of the truck, with parts broken away;

Fig. 4 is a section on line 4—4 of Fig. 1;

30 Fig. 5 is a plan view of one side of the truck showing the parts disassembled;

Fig. 6 is a section on line 6—6 of Fig. 3;

Fig. 7 is a section on line 7—7 of Fig. 3;

Fig. 8 is a horizontal section on line 8—8 of Fig. 7;

40 Fig. 9 is a vertical section on line 9—9 of Fig. 7;

Fig. 10 is a section on broken line 10—10 of Fig. 3; and

45 Figs 11 and 12 are diagrammatic views showing the angular arrangement of the swing hangers of the front and rear trucks, respectively.

Referring now to the drawings, the reference character 5 indicates a car truck comprising the frame 6, which is adapted to be

supported by the wheels 7, axles 8 and co-operating journal boxes 9 and 10, in the usual manner.

The frame 6 comprises a wheel piece or side frame member 14 at each side of the car, 55 which may be, and preferably is, an H-beam for the purpose of combining lightness and strength. Pedestals 15 and 16 are provided at the ends of the wheel piece. These pedestals each comprise the downwardly extending parallel arms 17 and 18, which are connected together at their lower ends by the tie members 19 in the usual manner. The upper portion of each pedestal is provided with an attaching bracket integral therewith, comprising the web portion 21, the outwardly extending flange 22 which is adapted to engage beneath the upper flange 23 of the wheel piece 14, and is rigidly attached thereto by suitable fastening means, as the rivets 24.

70 The web portion 21 of the attaching bracket is rigidly secured to the web of the wheel piece 14, the lower flange of the wheel piece being cut away adjacent each end thereof, as at 20 and 30, for receiving these web portions. Each web portion may be, and preferably is, provided with reinforcing ribs 25 for strengthening the web and wheel piece above the axle. An inwardly extending flange 26 at the lower part of the web portion 21 extends inwardly beneath the lower flange of the wheel piece 14, and is rigidly connected thereto by suitable bolts or rivets. The arms 17 and 18 are preferably provided with wear members 27, 28, extending about 75 the inner portion of the arms for engaging the inner portion of the arms for engaging the journal boxes 9 and 10 of the axles 8.

80 The wheel pieces 14 are rigidly connected together by the transoms or cross members 31, 32, which are preferably, though not necessarily, H-beams. The top and bottom flanges 33 and 34 of these cross members are removed at their ends so that the web portions 35, 36, will engage the webs of the wheel pieces 14 between the upper and lower flanges 85 thereof, and are rigidly connected thereto, as by welding, as indicated in Fig. 4.

90 Suitable gusset plates 37, 38, are provided for rigidly connecting the wheel pieces to said transoms on their upper surfaces. These 100

gusset plates are rigidly connected to the upper flanges of the wheel piece and the transoms in any suitable manner, as by rivets, as clearly indicated in Fig. 3. As shown in Fig. 1, the outer ends of these gusset plates overlap the attaching bracket of the pedestals, and are secured at their outer ends to the upper flange 23 by some of the same rivets 24 that attach the flange 22 of the pedestal attaching bracket to the upper flange of the wheel piece. The gusset plates are preferably provided with slots and upwardly extending apertured projections at each side thereof, to which the brake hang- 10 ers 39 are pivotally connected. The gusset plate 37 is provided with an upwardly ex- 15 tends through a slot in the gusset plate, 40 and as adjustably pivoted to the clevis 60. By means of this arrangement the pivot pins 20 for these links and levers are above the wheel pieces, whereby access may be readily had to these pivot pins and levers for removing 25 the same for replacement or repair. Since the brake shoes 70 are operated by the brake rod 80, the radius rod 90 and retracting spring 100, and the conventional links and levers in the usual manner, it is not thought 30 necessary to further describe this well known construction.

The gussets 37, 38, are also provided with slots and upwardly extending apertured pro- 35 jections 42 at each side thereof, to which the spring plank hangers or swing hangers 43 and 44 are adapted to be pivotally connected.

The inner ends of these gusset plates ex- 40 tend along the flanges of the transoms to a point overlapping the motor nose supporting bracket 47, as will presently appear (see Fig. 7). Portions of the upper and lower flanges 45 of the transom members 31, 32, are removed, as at 48, 49, for accommodating the spring or spring-plank hangers 43, 44 (see Fig. 5).

These gusset plates are also provided with inwardly extending projections 51, 52, which 50 lap past each other and are rigidly connected to the upper flange 23 of the wheel pieces 14, as clearly shown in Fig. 3 of the drawings. 55 By means of this arrangement these exten- 60 sions on the gusset plates assist materially in strengthening the wheel pieces at each side of the truck opposite the bolster 50. The pro- 65 jections 51, 52, are preferably welded to- 70 gether after they are applied, in order to pro- 75 vide a smooth joint which will not only strengthen the parts but also prevent the entrance of moisture and the like which would 80 cause rusting and deterioration of the parts. 85

If desired, these plates may be cast integral. Suitable gusset plates 57, 58, are also pro- 90 vided for rigidly connecting the lower flanges 95 of the wheel pieces and transoms, as shown more clearly in Fig. 5. As shown, these gus- 100 set plates are provided with spring seats 55

and 56, which are preferably integral therewith. These gussets are preferably integral because they are in tension, but it is understood they may be separate and also provided with lapping projections like the upper gus- 105 set plates, if desired. They are rigidly connected to the lower flange of the wheel pieces and are adapted to materially strengthen said pieces opposite the car bolster 50.

Each side of the truck is provided with an 110 equalizer member 59, which has its ends en- 115 gaging the journal boxes 9 and 10, respectively, and its central portion depressed, as at 61, as is usual in such constructions. Each of these equalizer members comprises a pair of 120 bars 62 and 63, held in spaced relation by the spacer members 64 at each end of the de- 125 pressed portion 61, and by a central spacer block 65. The spacer members 64 are pro- 130 vided on their upper ends with spring seats 135 66, which are adapted to be arranged below the spring seats 55, 56, and in vertical aline- 140 ment therewith, as clearly shown in Fig. 1 of the drawings.

Suitable springs 67 are positioned in said 145 seats for resiliently supporting the wheel pieces 14 from said equalizer member. The outer ends of the equalizer bars 62, 63, extend 150 on each side of the pedestals 15, 16, respec- 155 tively, as is usual in such constructions. Por- 160 tions of the lower flanges of the wheel pieces 14 are removed at each end thereof, as at 68, 165 69, for accommodating the outer ends of the 170 equalizer bar 63.

The bolster 50 is supported from the trans- 175 soms 31 and 32 by the swing hangers 43, 44, 180 which are connected at their lower ends by the connector member 71 on which the spring 185 seats 72 engage. A plurality of leaf springs 190 73 are interposed between the spring seats 195 72 and spring caps or seats 74 attached to the 200 under side of each end of the bolster 50. The 205 spring seats 72 are connected together by a 210 spring plank 75, which comprises the two 215 Z-bars 76, 77 (see Fig. 10), which are con- 220 nected together at their intermediate por- 225 tions by the plank 78 (see Fig. 6). The 230 plank 78 is provided with an opening 79 235 through which the king bolt 81, for connect- 240 ing body bolster 82 and the truck bolster 50, 245 may be inserted and removed. The king bolt 250 81 is adapted to be held in its elevated posi- 255 tion by suitable clips 81a, as clearly shown in 260 Fig. 10. The wheel pieces 14 are provided 265 with brackets or loop members 83, extending 270 inwardly for limiting the swinging move- 275 ment of the bolster 50 transversely of the 280 truck.

In the form of construction shown, suit- 285 able means are provided for supporting one 290 or more motors on the truck adjacent to the 295 bolster construction. Only one motor is 300 shown. As shown more or less diagrammat- 305 ically in Fig. 3, the motor 84 is mounted on 310 the axle 8 in the usual manner. Since the 315

specific features of this mounting constitute no part of the present invention, it is not thought necessary to illustrate or describe the same. If two motors are employed one is 5 mounted on each axle 8.

Any well known or conventional type of mounting that will permit a limited vertical movement of the inner end or nose of the motor may be employed. Since the motor nose 10 supports 86 at each side of the bolster are substantially the same, only one need be described. This support comprises the body portion 87 (see Figs. 5, 7, 9 and 10). The body portion 87 is provided with an upwardly extending attaching portion 88, having the laterally extending wings 89 which are rigidly connected to the web of the adjacent transom, as by being riveted thereto, as clearly shown in Fig. 7 of the drawings. The lower 20 flange of the transom is cut away, as at 91 (see Fig. 9) to accommodate the upwardly extending portion 88.

The body portion 87 is also provided with an inwardly extending horizontal flange 92, 25 and with an outwardly extending horizontal flange 93 at each side of the upwardly extending portion 88, which are rigidly connected to the lower flange of the transoms, as by being riveted thereto. Reinforcing ribs 94 30 (see Fig. 9) are provided for reinforcing the body portion 87 and the flange 92. The lower end of the body portion 87 is provided at each side thereof with inwardly extending flanges 95, to which are attached connecting members 25 96, which extend from one motor nose support to the other beneath the spring planks 75, and not only brace the two motor nose supports but also constitute a spring plank safety hanger.

40 Suitable means are provided for resiliently supporting the motor nose from the motor nose support 86. In the form of the device selected to illustrate one embodiment of the invention, the body portion 87 is provided with a pair of outwardly extending flanges 97, adjacent to the under side of the corresponding transom, and with a pair of outwardly extending flanges 98, adjacent to the lower end of the body portion 87. These 45 flanges are arranged in pairs in spaced relation. The corresponding members of each pair are in vertical alinement, and are provided with openings through which bolts 99 are adapted to extend. The flanges 97 50 are provided with vertically extending reinforcing ribs 97a, and the flanges 98 are also provided with corresponding reinforcing ribs 101.

A suitable resilient unit is mounted on the 60 bolts 99 between the flanges 97 and 98. As shown, this mechanism comprises a pair of plates 102 and 103 adjacent to the flanges 97, 98, and a pair of spring followers 104 and 105 between which is interposed a plurality of 65 springs 106. The plates and followers are

mounted on the bolts 99, about which the springs 106 extend. The springs 106 encircle bolts 108, which extend through the followers 104 and 105. The plate 103 is provided with enlarged openings in alinement with the bolts 108, whereby when the device is compressed the bolt heads may extend through said opening. The followers 104, 105, are provided with countersunk openings for receiving the heads and nuts of the bolts 108. These followers are also provided with bosses extending about the bolt openings for positioning the springs. 70 75

The inner end of the motor or motor nose 109 is provided with a lug 110 adjacent its upper portion, which extends inwardly therefrom and is adapted to rest on the plate 102 for resiliently supporting the inner end of the motor. 80

Suitable means are provided for yieldingly 85 resisting the upward movement of the motor at its inner end. This means, as shown, comprises a lug 111 extending forwardly from the lower portion of the motor nose, and is adapted to engage beneath the plate 103, 90 which resiliently resists the upward movement of said lug. It will be noted that the plates, springs and spring followers are so constructed that they are reversible, that is, it is immaterial which follower and plate are 95 in the uppermost position.

In the operation of cars there is more or less swinging or swaying of the car body relative to the truck frame, due to the track curvature and the inequalities in the roadbed. And where, as in the present invention, motor generator sets for operating motors are mounted at one end only of the car, there is an unequal distribution of the weight, the end of the car 100 opposite the motors being much lighter than the motor end, or where, for any reason, the car is so constructed that one end is heavier than the other, the oscillation or swinging movement at the two ends of the car if similarly mounted, will not synchronize. These 105 non-synchronizing oscillations of the ends of the car are more or less detrimental to the car and are unpleasant to the passengers.

It has been found that the swing or spring board hangers 43 at the light end of the car 110 can be arranged at such an angle as to cause the oscillations at both ends of the car to synchronize. In Figs. 11 and 12 this arrangement is shown diagrammatically. In Fig. 11 the transom at the heavy or motor end of the car is shown by the line 31, the swing or spring board hangers by the lines 43, and the spring board by the line 75. 115 120

The arrangement of these parts at the light end of the car is shown in Fig. 12, in which the transom and links are as described above, but the links 43 are at a slightly greater angle. The difference in the angle of the links or hangers 43 is exaggerated for the purpose of illustration. The pivots on the transoms 31 125 130

will be closer together in Fig. 12 than in Fig. 1, as indicated on said figures. The differential angle will, of course, vary with the different lengths, weights and types of cars, but in all cases the angle that the hangers 43 make with the vertical will be greater at the lighter end of the car. When the hangers 43 are arranged as in Figs. 11 and 12, it will readily be seen that for the same angular movement of these two sets of hangers the center of gravity of the lighter end will move through a greater vertical height than the heavier end. Since the vertical distance moved by the center of gravity of the car ends for any given angular movement of these hangers will vary as the sine of the angle, and since the sine varies more rapidly as the hangers approach the horizontal, it follows that these two sets of hangers may be so arranged as to synchronize in their oscillations.

It will thus be seen that a car truck is provided that is built up of separate comparatively light units, and the parts so connected and arranged as to form a light truck frame that combines lightness and rigidity.

It is thought from the foregoing, taken in connection with the accompanying drawings, that the construction and operation of my device will be apparent to those skilled in the art, and that various changes in size, shape, proportion and details of construction may be made without departing from the spirit and scope of the appended claims.

I claim as my invention—

1. In a railway truck, a pair of wheel pieces, a pair of transoms rigidly connected to said wheel pieces, a pair of gusset plates secured to the top portions of said wheel pieces and transoms, said plates having lapped portions on said wheel pieces for reinforcing the same.

2. In a railway truck, a pair of H-beams constituting wheel pieces, a pair of transoms formed from H-beams, said transoms having their flanges removed at their ends and having their web portions rigidly attached to said wheel pieces, a pair of gusset plates secured to the upper and lower flanges of said transoms and wheel pieces, said upper gusset plates being provided with upwardly extending apertured projections to which the bolster swing hangers and brake hangers and levers are attached.

3. In a railway truck, a pair of wheel pieces, a pair of transoms rigidly connected to said wheel pieces, a pair of gusset plates for connecting the upper portions of said transoms and wheel pieces, and a pair of gusset plates integrally connected for connecting the lower portions of said wheel pieces and transoms together, said first-named gusset plates being provided with inwardly extending projections forlapping that of the adjacent plate.

4. In a railway truck, a pair of wheel

pieces, gusset plates for connecting the upper and lower portions of said wheel pieces and transoms together, a pedestal casting having laterally extending flanges secured to each end portion of each of said wheel pieces, the gusset plates at the upper portion of said wheel pieces overlapping the flanges of said pedestal casting and rivet means for rigidly connecting said gusset plates and flanges together.

5. In a railway car having a truck provided with transom members, a bolster, a spring plank, and resilient means between said plank and bolster, a motor nose supporting bracket mounted on said transoms at each side of said bolster, and tie members for connecting the lower ends of said brackets, said tie members extending beneath said spring plank.

6. A motor nose support for a truck transom comprising a transom provided with a lower flange having a cutaway portion, a motor nose supporting bracket rigidly connected to said transom and extending downwardly through said cut-away portion, flanges on said bracket extending beneath and rigidly secured to the flanges of said transom, laterally extending projections on said bracket arranged in vertical alignment, and resilient motor nose supporting mechanism between said projections.

7. In combination, a railway truck comprising an axle, a transom comprising a web portion and a flange on its lower portion, a motor movably mounted on said axle, a supporting bracket having laterally extending lugs, a spring assembly between said lugs, and a pair of lugs on the inner end of said motor for engaging above and below said spring assembly for supporting and positioning the inner end of said motor, said bracket having its upper end connected to said web portion and provided with a laterally extending flange rigidly connected to the flange on said transom.

8. A motor nose supporting device comprising a bracket having outwardly extending apertured lug members for receiving a resilient unit between said members, said bracket having an outwardly extending flange adjacent its upper end and an inwardly extending flange on its lower end, and a reinforcing rib for said last-named flange.

9. In combination, a truck frame comprising wheel pieces, transoms connecting said wheel pieces, gusset plates connected to said wheel pieces and transoms, and a motor nose supporting bracket rigidly connected to said transom, said bracket having laterally extending portions lapping the inner ends of said gusset plates for reinforcing said transoms opposite said motor.

10. In combination, a railway truck comprising an axle, a transom comprising an I-beam having its lower, outer flange cut away

to provide a recess, a motor movably mounted on said axle, said motor being provided with 5
motor nose supporting lugs, means on said transom for supporting the inner end of said motor, said means comprising a bracket connected to the web of said I-beam and extending downward through said recess and provided with an inwardly extending flange rigidly secured to the inwardly extending bottom flange of said I-beam, said bracket having an inwardly extending flange on its lower 10
end, a tie member connected to said last-named flange, said bracket having outwardly extending lugs, and a spring unit between 15
said lugs and adapted to be engaged by said motor nose supporting lugs.

11. In a railway truck, a pair of H-beams constituting wheel pieces, a pair of transoms formed from H-beams, said transoms having 20
portions of their flanges removed at their ends and having their web portions rigidly attached to said wheel pieces, a pair of gusset plates secured to the upper and lower flanges of said transoms, the upper gusset 25
plates having laterally extending projections extending past each other on said wheel pieces and the lower gusset plates being integral, and motor nose supports secured to 30
said transoms, said supports having projections lapping past said gusset plates on said transoms for reinforcing the intermediate portions of said transoms.

12. In a railway truck frame, a transom having a vertical web, top and bottom members 35
extending horizontally inwardly and outwardly from said web, and a motor supporting bracket projecting from one side of said transom beyond the corresponding outer edges of said members.

13. In a railway truck, a frame including 40
spaced transoms having a vertical web and top and bottom horizontal members extending from at least one of said webs inwardly toward the longitudinal center of said frame, a movable bolster between said transoms, and a motor support bracket element projecting outwardly from and below the bottom of the transom having said members.

14. In a railway truck, a frame including 45
spaced transoms, each of said transoms having a vertical web, a movable bolster between said transoms, a motor support bracket element projecting below the bottom of at least one of said transoms, and a tie member extending between said transoms intermediate the ends of the latter and below said bolster to rigidly hold said transoms in spaced positions.

15. In a railway truck, a frame, spaced 50
transoms, a movable bolster between said transoms, a bracket element on each of said transoms for supporting a motor and projecting below said transoms, and a tie member 55
extending longitudinally of said frame,

said tie member connecting said bracket elements.

16. A pedestal for a railway truck frame comprising a body portion having apertures for connecting the same to the web of a 70
flanged side frame member, a pair of arms rigid with said body portion and extending downwardly therefrom, an apertured flange extending inwardly from said body portion for connection with the bottom flange of said 75
side frame member, an outwardly extending, apertured flange at the upper end of said body portion for connection with the upper flange of said side frame member, and laterally extending upstanding ribs on said body 80
portion for reinforcing said last-named flange.

17. In a railway truck frame, a side frame member having a web portion and upper and lower flanges, a pedestal comprising a body 85
portion rigidly connected to said web portion, arms integral with said body portion and extending downwardly therefrom, a pair of flanges extending laterally from said body portion, means for rigidly connecting one of 90
said flanges to the lower flange of said side frame member and the other flange to the upper flange of said side frame member.

18. In a truck frame, a side frame member at each side of the frame, each comprising a 95
web portion having an upper and a lower outwardly extending flange, the lower flange having portions cut away at each end portion of said member to form recesses, a pedestal in each recess, each pedestal having a body 100
portion rigidly secured to said web portion and provided with a flange engaging beneath the upper flange of said side frame member, arms integral with said body portion and extending downwardly therefrom for receiving 105
a journal box, a transom for connecting said side frame members, a pair of gusset plates having lapping inner ends rigidly connected to said transom, and means for rigidly connecting said gusset plates, side frame members and upper flange together, and lower 110
gusset plates for connecting said side frame members and transom together, said last-named gusset plates being provided with spring seats, and means including springs engaging 115
said seats for supporting said wheel members.

19. In a railway truck, a pair of wheel pieces, said wheel pieces having upper and lower flanges extending laterally therefrom, a 120
plurality of pedestals for each wheel piece, each pedestal having a pair of depending arms, a web portion rigid with said arms, a flange extending beneath a flange of the wheel piece and rigidly connected thereto laterally therefrom, one of the flanges of each wheel piece having portions cut away for receiving the web portions of the corresponding pedestals, said web portions of said pedestals being 125
rigidly connected to the wheel pieces between 130

the flanges thereof, a pair of transom members rigidly connected to said wheel pieces, gusset plates rigidly secured to said transom members and wheel pieces, said plates extending along said wheel pieces the entire distance between said transoms and beyond the same in opposite directions for reinforcing said wheel pieces.

20. In a railway truck, a pair of H-beams constituting wheel pieces, a pair of transoms 10 formed from H-beams, said transoms having their flanges removed at their ends and having their web portions rigidly attached to said wheel pieces, a pair of gusset plates secured to the upper and lower flanges of said 15 transoms and wheel pieces for connecting said transoms and wheel pieces together and for reinforcing said wheel pieces, the lower flanges of said wheel pieces being cut away 20 at a plurality of places to form recesses, a pedestal extending upwardly through each recess and rigidly secured to the web portion of the corresponding wheel piece, each pedestal having a flange extending beneath and 25 rigidly secured to the lower flange of the corresponding wheel piece and provided with depending arms.

In testimony whereof I affix my signature.
WILLIAM H. MUSSEY.
